UNITED STATES PATENT OFFICE.

EDWARD L. ACKERMAN, OF ROMEO, MICHIGAN, ASSIGNOR, BY DIRECT AND MESNE ASSIGNMENTS, TO ACKERMAN-BLAESSER-FEZZEY, INC., OF DETROIT, MICHIGAN, A CORPORATION OF MICHIGAN.

SASH-OPERATING MECHANISM.

Application filed February 26, 1925. Serial No. 11,662.

This invention relates to sash operating mechanisms and the object of the invention is to provide a sash operating mechanism in which the sash may be locked at any point within its path of travel. Another object of the invention is to provide a sash operating mechanism in which the mechanism is unlocked at the beginning of rotation of the operating crank and is locked again upon cessation of rotation thereof. A further object of the invention is to provide a sash operating mechanism in which the sash is spring supported at two points throughout the path of travel in order to counterbalance the sash and allow it to be raised as easily as lowered. A further object of the invention is to provide a sash operating mechanism comprising a pivoted lever adapted to be raised or lowered by rotation of the crank to raise or lower the sash. Another object of the invention is to provide a sash operating mechanism in which the sash may be completely lowered and raised by one complete rotation of the crank. These objects and the several novel features of the invention are hereinafter more fully described and claimed and the preferred form of construction by which these objects are attained is shown in the accompanying drawings in which—

Fig. 1 is a view of the sash operating mechanism from the interior of the automobile body with the sash in the raised position.

Fig. 2 is a section taken on line 2—2 of Fig. 1.

Fig. 3 is a section similar to Fig. 2 showing the device in the unlocked position.

Fig. 4 is a section taken on line 4—4 of Fig. 2.

Fig. 5 is a side elevation of the sash operating mechanism.

Fig. 6 is a section similar to Fig. 1 showing the sash in the lowered position.

As shown in Fig. 1 a frame 1 is provided having a window glass 2 slidable vertically therein and provided with a sash 3 having a way 4 therein. A cross member 5 is provided for the frame and a metal plate 6 is secured to the member 5, the member 5 being cut away behind the plate 6 as shown in dotted lines 7 in Fig. 1. A lever 8 shown in Figs. 1 and 2 is pivotally mounted on the inner side of the plate 6 at 9 and is provided

with a slot 10 in the end thereof in which a pin 11 is adapted to ride. This pin 11, as shown in Fig. 2 is mounted in a block 12 which is slidably mounted on the vertical guide rod 13. The guide rod 13 is secured by means of a nut 14 shown in Figs. 1 and 5 to the plate 6 at the upper end and at the lower end is secured in a block 15 mounted on the lower frame member or sill 16. To limit movement of the block 12 on the guide rod 13 a slot 17 is provided in the plate 6 and the extreme end of the pin 11 extends through this slot as shown in Figs. 1, 2 and 5. Pivotally mounted on the pin 11 on opposite sides of the arm 8 is a pair of rods 18 and 19 the rod 18 being pivotally connected at 20 to a lever 21 and the rod 19 being pivotally connected at 22 to a lever 23. The levers 21 and 23 are pivoted on a common center 24 on the block 15 which is secured to the lower frame member or sill 16. A block 25 is provided which is slidable vertically of the rod 13 and a pair of crossed arms 26 and 27 are pivotally mounted at their intersection on the block 25. At the lower end the arm 26 is pivotally connected to the arm 23 at 28 and the other arm 27 is pivotally connected to the arm 21 at 29. If desired a flat coiled spring indicated by dotted lines 30 may be provided at this point which tends to extend the arms though the device will operate efficiently without the use of the spring. At the upper end the arms 26 and 27 are outturned and are each provided with a roller 31 riding in the way 4 in the sash 3 as shown in Figs. 1 and 5. By this construction by raising or lowering the rods 18 and 19 the crossed arms may be extended or contracted to raise or lower the sash. The plate 6 is provided with a raised portion 32 in the center shown in Figs. 1 and 2 and the portion of the plate about this raised portion is provided with a series of apertures 33 arranged circumferentially. A member 34 is rotatably mounted in this raised portion and is provided with squared end 35 to which a crank may be secured. This member 34 is provided with a squared portion 36 on which a circular plate 37 is mounted, the plate being apertured to fit the squared portion 36. The member 34 is also provided with a portion 50 which fits the central aperture in the raised portion 32 and allows rotation of the member 34 in the plate 6. The

member 34 is also provided with a cylindrical portion 38 having a flange 39 at the end and a coiled spring 40 is positioned on the portion 38 and tends to hold the plate 41 in engagement with the plate 37. The plate 41 is provided with a series of ball recesses 42 in each of which a ball 43 is mounted. These recesses as shown in Fig. 4 are longer than the ball and the bottom of the recesses are inclined toward the center as shown. The plate 37 is provided with a recess 44 fitting each ball as shown in Fig. 4 so that the balls are carried by the plate 37. The plate 41 as shown in dotted lines in Fig. 1 is provided 15 with an extending pin 45 which extends through a slot 46 provided in the plate 37 so that the plate 37 may be turned in relation to the plate 41 to a slight extent, the plate 41 being rotatably mounted in relation to the 20 crank while the plate 37 is secured thereto. The plate 41 is provided with a pair of upwardly extending diametrically opposite lugs 47 which normally engage in the apertures 33 as shown in Figs. 1 and 2 thus preventing movement of the sash operating mechanism. The plate 41 is also provided with a pin 48 which engages in the cam slot 49 in the lever 8 and controls movement thereof.

To operate the device the crank is turned which turns the member 34 and plate 37 secured to the portion 36 thereof. The plate 37 carries the balls 43 which travel up the inclined sides of the recesses 42 thus pressing the plate 41 outwardly against the tension of the spring 40 and withdraws the lugs 47 from the apertures 33. In this period of travel the pin 45 travels around to the end of the slot 46 and the pin engages the end of the slot and turns the plate 41 with the plate 37. As the plate 41 is turned the pin 48 which is secured to the plate 41 and extends through the slot 49 in the arm 8 is turned thus moving the arm 8 downward on its pivot 9 and moving the member 12 downwardly on the guide rod 13. The rods 18 and 19 which are connected at the upper end to the block 12 force the arms 21 and 23 outwardly on their pivots until the sash reaches the lowermost position shown in Fig. 6. This movement of the sash from the raised position to the lowered position is accomplished by a one-half rotation of the crank and by returning the crank from the position shown in Fig. 6 to that shown in Fig. 1 the sash is again raised. Upon release of the crank at any position the tension of the spring 40 forces the plate 41 to move about so that the balls 44 are positioned in the bottom or deepest part of the recesses 42 which causes the lugs 47 to move into the respective apertures 33 and thus lock the device in position the pin 45 being then positioned in the center of the slot 46. By this arrangement the sash may be raised

or lowered by a half turn of the crank and by providing the springs 30 the raising of the sash may be accomplished with as much ease as the lowering of the sash. By providing a sash operating mechanism composed practically entirely of sheet metal parts and rods a construction of low manufacturing cost is provided which has at the same time all the advantages of higher priced mechanism of this type with the further advantages of locking at any point.

From the foregoing description it becomes evident that the device is very simple and efficient in operation, will not readily get out of order, is composed of few parts and is of consequent low manufacturing cost, and provides a device which accomplishes the objects described.

Having thus fully described my invention, its utility and mode of operation, what I claim and desire to secure by Letters Patent of the United States is—

1. In a sash operating mechanism, a frame, a sash slidably mounted in the frame and provided with a slot in the lower edge thereof, a pair of levers mounted on a common pivot on the lower part of the frame, a pair of crossed arms each pivoted to the upper end of one of the levers, a guide rod extending vertically from the pivot point of the levers, a member slidable on the guide rod, the crossed arms being pivoted at their intersection on the slidable member and being provided with rollers at the upper end riding in the slot of the sash, a vertically movable member mounted on the guide rod, a pair of operating rods pivotally connected to the vertically movable member, each operating rod being pivoted to one of the levers intermediate its ends, a lever pivotally mounted on the frame and supporting the vertically movable member in its outer end, the said lever being provided with a slot intermediate its ends, a plate provided with a slot, a crank for rotating the plate, a second plate rotatable in relation to the slotted plate and having a pin engaging in the slot of the first plate, the rotatable plate being provided with a second pin engaging in the slot of the lever, and means whereby the second plate may be locked or unlocked from rotation.

2. In a sash operating mechanism, a frame, a sash slidably mounted in the frame, and provided with a slot in the lower edge thereof, a pair of levers mounted on a common pivot on the lower part of the frame, a pair of crossed arms each pivoted to the upper end of one of the levers, a guide rod extending vertically from the pivot point of the levers, a member slidable on the guide rod, the crossed arms being pivoted at their intersection on the slidable member and being provided with rollers at the upper end riding in the slot of the sash, a vertically

- movable member, a pair of operating rods pivotally connected to the vertically movable member, each operating rod being pivoted to one of the levers intermediate its ends, a lever pivotally mounted on the frame and supporting the vertically movable member in its outer end, the said lever being provided with a slot intermediate its ends, a plate provided with a pin extending into the slot, a crank for rotating the plate, and means whereby cessation of rotation of the crank locks the plate in position and subsequent movement of the crank unlocks the plate to rotation by the crank.
- 5 3. In a sash operating mechanism, a frame, a sash slidably mounted in the frame, and provided with a way in the lower edge thereof, a pair of levers mounted on a common pivot on the lower part of the frame, a pair 20 of crossed arms each pivoted to the upper end of one of the levers, a guide rod extending vertically from the pivot point of the levers, a member slidable on the guide rod, the crossed arms being pivoted at their intersection on the slidable member and being provided with rollers at the upper end riding in the way of the sash, a vertically movable member, a pair of operating rods pivoted on the vertically movable member, each 25 operating rod being pivoted to one of the levers intermediate its ends, a lever pivotally mounted on the frame, the outer end of the lever being connected with the vertically movable member, and crank operated means for turning the lever on its pivot.
4. In a sash operating mechanism, a frame, a sash slidably mounted in the frame and provided with a way in the lower edge thereof, a pair of levers mounted on a common 40 pivot on the lower part of the frame, a pair of crossed arms each pivoted to the upper end of one of the levers, a member slidable on the guide rod, the crossed arms being pivoted at their intersection on the slidable member and being provided with rollers at the upper end riding in the way of the sash, a vertically movable member, a pair of operating rods pivoted on the vertically movable member, each operating rod being pivoted to one of the levers intermediate its ends, and means for 45 raising or lowering the vertically movable member.
5. In a sash operating mechanism, a frame, a sash slidably mounted in the frame and provided with a way in the lower edge thereof, a pair of levers mounted on a common pivot in the lower part of the frame, a pair of crossed arms each pivoted to the upper end of one of the levers, a guide rod extending vertically from the pivot point of the levers, a member slidable on the guide rod, the crossed arms being pivoted at their intersection on the slidable member and being provided with rollers at the upper end riding in the way of the sash, a vertically movable member, a pair of operating rods pivoted on the vertically movable member, each operating rod being pivoted to one of the levers intermediate its ends, and means for raising or lowering the vertically movable member.
6. In a sash operating mechanism, a frame, a sash slidably mounted in the frame and provided with a way in the lower edge thereof, a pair of levers mounted on a common pivot on the lower part of the frame, a pair of crossed arms each pivoted to the upper end of one of the levers, the arms being pivoted together at the point of intersection and being provided with rollers at the upper end riding in the slot of the sash, a vertically movable member, a pair of operating rods pivotally connected to the vertically movable member, each operating rod being pivoted to one of the levers intermediate its ends, and means for raising or lowering the vertically movable member.
7. In a sash operating mechanism, a frame, a sash slidably mounted in the frame, a pair of crossed arms being pivoted at their intersection on the slidable member and being provided with rollers at the upper end riding in the way of the sash, a second slidable member on the guide rod, a pair of operating rods pivoted on the second slidable member, each operating rod being pivoted to one of the levers intermediate its ends, and means for moving the second slidable member longitudinally of the guide rod.
8. In a sash operating mechanism, a frame, a sash slidably mounted in the frame and provided with a way in the lower edge thereof, a pair of levers pivotally mounted on the lower part of the frame, an upright guide rod secured to the frame, a member slidable on the guide rod, a pair of crossed arms pivoted at their intersection on the said slidable member, each arm being pivotally connected to one of the levers a second slidable member on the said guide rod, a pair of rods pivotally mounted on the second slidable member and pivoted at the lower ends to the said levers, the upper ends of the said arms being provided with rollers riding in the way of the sash, and means for moving the second slidable member longitudinally of the guide rod.
9. In a sash operating mechanism, a frame, a sash slidably mounted in the frame and provided with a way in the lower edge thereof, a pair of levers mounted on a common pivot on the lower part of the frame, a pair of crossed arms each pivoted to the upper end of one of the levers, a guide rod extending vertically from the pivot point of the levers, a member slidable on the guide rod, the crossed arms being pivoted at their intersection on the slidable member and being provided with rollers at the upper end riding in the way of the sash, a vertically movable member, a pair of operating rods pivoted on the vertically movable member, each operating rod being pivoted to one of the levers intermediate its ends, and means for raising or lowering the vertically movable member.

of levers mounted on a common pivot on the lower part of the frame, a pair of crossed arms each pivoted to the upper end of one of the levers, a guide rod extending vertically from the pivot point of the levers, a member slidable on the guide rod the crossed arms being pivoted at their intersection on the slidable member, the upper ends of the crossed arms being connected with the sash,

10 a vertically movable member, a pair of operating rods pivoted on the vertically movable member, each operating rod being pivoted to one of the levers intermediate its ends and means for raising or lowering the vertically movable member.

15 In testimony whereof, I sign this specification.

EDWARD L. ACKERMAN.
